UNITED STATES PATENT OFFICE.

CARL HOFFMAN, OF ALLENtown, PENNSYLVANIA.

DOOR-BOLT.

1,388,712.

Specification of Letters Patent. Patented Aug. 23, 1921.

Application filed July 16, 1920. Serial No. 396,696.

To all whom it may concern:

Be it known that I, CARL HOFFMAN, of Allentown, in the county of Lehigh and State of Pennsylvania, have invented certain new and useful Improvements in Door-Bolts; and I do hereby declare the following to be a full, clear, and exact description of the invention, such as will enable others skilled in the art to which it appertains to 10 make and use the same.

My invention relates to locking devices for doors and more particularly to such as are adapted for locking the door in its fully closed position as well as in a partially 15 opened position.

The object of my invention is to provide an improved, simple, and highly efficient lock of this character embodying but few parts which will not readily get out of 20 order, the coöperating parts of the locks being so arranged that they may not be easily tampered with.

In the drawings, Figure 1 is a view in perspective showing my improved lock in 25 the position it occupies in locking the door in fully closed position, a portion of a door and its casing being shown. Fig. 2 is a cross sectional view of a portion of a door and its casing with the locking bolt in position where the door may be partly opened. Fig. 3 is a view similar to Fig. 2 with the 30 door locked in a slightly opened position. Fig. 4 is a bottom plan view of the bolt and auxiliary keeper, showing the catch for 35 preventing turning of the bolt.

At 1 I have indicated a casing which includes a slideway for a bolt 2 having at one end a manipulating handle 3. At its opposite end the bolt has a lateral projecting stud 40 4 which when the bolt is turned axially so as to bring its handle 3 in an upright position will assume a similar position. As shown in Fig. 1 the parts are in the position just described and the extreme end 5 of the bolt 45 is within the keeper 6 of the striker plate. Extending outward from the striker plate are a pair of vertically alined ears 7 which form the pivotal support for an auxiliary keeper 8. I have shown this auxiliary keeper

50 formed from a single piece of metal bent back upon itself, its ends being pivoted to the ears 7 and the bowed portion 9 at its opposite end forming a stop for the bolt. Stops 10, 12, on the auxiliary keeper 55 operate with the stud 4 in maintaining the door locked in a partially opened position, a

catch 13 on the casing 1 being designed to be moved into engagement with the handle 3 to prevent the bolt being turned when the parts are in the position described. 60

In the use of my improved door bolt, with the parts as shown in Fig. 1, the door is locked in its fully closed position, and the stud 4 being in line with the upper of the ears 7 prevents the bolt being retracted. If 65 the bolt is moved to the point where it engages the ear it will have left the keeper 6 and the door may be opened, the stud riding along the ear and then engaging the auxiliary keeper 8. Continued opening of the 70 door will cause the keeper to turn on its pivot, the stud continuing to engage the keeper. It will be seen that this construction permits the door to be released for slight opening, but prevents a full opening. 75 The measure of protection afforded by such a structure is apparent. The door is not fully released from its lock until the bolt is turned so that its stud is freed of the ears of the auxiliary keeper. Frequently it is 80 desirable to have a door slightly opened for purposes of ventilation and it is desirable that it may be locked against undue opening as well as against slamming. The auxiliary keeper is useful to this end. With the bolt 85 engaging the outermost portion of the auxiliary keeper it is turned so that its stud 4 projects downward, as indicated in Fig. 4, and into engagement with the stop 12. So turned the handle 3 is pointed downwardly 90 and is in a position to be engaged by the catch 13 which will prevent the bolt being turned. The stop 10 will coöperate in a similar manner as the stop 12 to prevent 95 slamming of the door.

The advantages of my improved lock will be apparent. It will be seen that I have provided a positive door lock as well as a means for retaining the door in a partially locked position, and I have also provided in this 100 latter means a way by which the door may be fastened for ventilation purposes without the necessity of employing any stop at the base of the door for contacting with the floor. 105

I claim as my invention:

1. A fastening device for a door including a sliding bolt, a keeper on the door frame to receive said bolt, an auxiliary keeper also on the door frame and with which said bolt 110 may be caused to engage to lock the door in a partly opened position, and means in part

carried by said bolt and in part by said auxiliary keeper to maintain said bolt and said auxiliary keeper in locked engagement, said bolt being adapted for turning movement to free it of engagement with said auxiliary keeper.

2. A fastening device for a door including a sliding and rotatable bolt having a laterally projecting stud near one end, a keeper 10 on the outer frame to receive said bolt, an auxiliary keeper also on the door frame and with which said bolt may be caused to engage to lock the door in a partly opened position, a stop on said auxiliary keeper with 15 which said stud is designed to coöperate to maintain said bolt in locking engagement with said auxiliary keeper, and a catch to prevent turning of said bolt to disengage the said stud and stop.

20 3. A fastening device for a door including

a sliding and rotatable bolt having a laterally projecting stud near one end and a handle at its opposite end, a keeper on the door frame to receive said bolt to lock the door in closed position, an auxiliary keeper 25 also on the door frame and having a hinged connection therewith and with which said bolt may be caused to engage to lock the door in a partly opened position, stops on said auxiliary keeper with which said stud 30 may be caused to engage upon turning the bolt to maintain the bolt in locking engagement with said auxiliary keeper, and a catch coöoperating with the handle of the bolt to prevent turning of the bolt to disengage said 35 stud and stop.

In testimony whereof I have signed this specification.

CARL HOFFMAN.
